UNITED STATES PATENT OFFICE.

GEORGE HENRY HERMANSEN, OF SACRAMENTO, CALIFORNIA.

PAPER-GAGE FOR TYPE-WRITERS.

1,245,916.

Specification of Letters Patent.

Patented Nov. 6, 1917.

Application filed December 11, 1914. Serial No. 876,748.

To all whom it may concern:

Be it known that I, GEORGE H. HERMANSEN, a citizen of the United States of America, and a resident of Sacramento, county 5 of Sacramento, and State of California, have invented certain new and useful Improvements in Paper-Gages for Type-Writers, of which the following is a full and clear specification.

10 My invention relates to improvements in paper gages adapted to enable the operator of a typewriter to determine, through an automatic signal: first, when the operator arrives at the last or bottom line to be written on a sheet of paper of any length on which a bottom margin of any predetermined width is desired; second, to enable the operator to see at a glance how many more lines remain to be written on a page, thus 15 saving time and paper and securing greater neatness and uniformity in the writing to be done; and, third, to enable the operator to write any given number of lines provided for without fear of running past the number of lines desired. The invention has for 20 its further object to provide simple means to enable the operator to center any given number of lines on a given size paper, whether the lines be single, double or triple space.

30 I attain these objects by the mechanism illustrated in the accompanying drawing, in which similar letters refer to similar parts throughout the several views, which views are described as follows:

35 Figure 1 is a side elevation of my device applied to an Underwood typewriter, model No. 5;

Fig. 2 is a front view of my device detached from the typewriter;

40 Fig. 3 is a back view of the same;

Fig. 4 is a detail view of a gage plate for assisting the operator in centering the reading matter on a page; and

45 Figs. 5, 6 and 7 are views of details hereinafter more particularly described.

In the drawings annexed, *a* designates a main plate which is connected by hinges *b* to the lower section *a'* of the main plate, this lower section being provided with forwardly-extending ears *c* to enable it to be fastened (by screws *d*) to the rear edge of the top of the frame of the typewriter, these ears being so positioned that the supporting plate (consisting of the sections *a*, *a'*) will lie at an angle extending upwardly and backwardly from the machine frame. The

hinges *b* enable the upper section of the supporting plate to be folded down over the top of the machine to enable the machine to be covered in the usual way. If 60 a means is desired to lock the upper section in its operative position, I employ the spring catches *e* which are adapted to snap through eyes *f* carried by the lower section of the supporting plate. 65

On the face of the supporting plate is marked a vertical inch-gage *C* and alongside the same is marked off a gage *B* for indicating single spacing, there being, as usual six single spaces to an inch. Adjacent the 70 inch scale, the supporting plate is vertically slotted, and back of this slot is arranged a ratchet bar *g*. Slidably mounted on this bar *g* is a slide *h* provided with spring pawls *i* adapted to engage the teeth of bar *g* and thus be held in any position which it may be adjusted to along the bar *g*. The front end of the slide *h* works in the aforesaid slot and carries a trip lever *A* which extends forwardly through the slot. This lever is 80 pivotally mounted on the slide and tends to swing downwardly, its outer end being curved downwardly. This lever carries an electric contact *j* which is adapted when the lever *A* is raised to a horizontal position to 85 make electric contact with a companion contact *k* mounted on the slide *h* but insulated therefrom. The contact *k* is provided with a lateral finger *l* which is connected electrically to a conductor *m* leading from the battery *n* and containing a buzzer or other electric signal *o*, the other branch *p* of the circuit leading from the battery to a ground on the frame of the machine. It will thus be seen that when the trip lever *A* is raised, its 90 contact *j* will make contact with contact *k* and thus complete the circuit through the 95 buzzer, thereby producing an audible alarm.

The object in downwardly curving the outer end of the lever *A* is to permit the tail end of the paper to slide down the same without operating the signal while the paper is passing through the machine. After the paper has passed through the machine sufficiently to have the forward or ascending end lie by gravity against the front face of the supporting plate, it will be seen that as the paper is fed through the machine this forward edge of the paper will slide up the front face of the supporting plate, and that 100 when it raises the trip lever *A* contact will be made and the alarm will be sounded. 105

The position of the trip lever with reference to the scales B and C will be determined by the length of the paper and the bottom margin desired. For instance, if it be desired to warn the operator when the writing point on the paper is three inches from the lower edge of a thirteen-inch sheet, the trip lever will be set to operate the alarm when the ascending end of the sheet reaches 10 on the inch scale, the scale shown being adapted for paper up to thirteen inches in length. When the trip lever is thus set at 10, it will be observed that the alarm will be sounded when the three-inch bottom margin is reached. The adjacent scale B will indicate at a glance to the operator the number of single spaces that may yet be written on the page.

On the opposite side of the above described slot, I form a depression in the face of the supporting plate sufficiently deep to receive a gage plate *q*, shown in detail in Fig. 4, this gage plate being adapted to slide up and down in said depression, means being provided for locking it in any of its adjusted positions. The depression in which this plate slides extends down into the lower section *a'* of the supporting plate. In the lower part of the depression a scale is marked off for paper having a length from seven to thirteen inches. Any suitable means may be employed for locking this gage plate in its adjusted positions; as an instance, I illustrate a locking means similar to the locking means employed for locking the slide *h*, these means consisting of a slide *r* whose front edge works through a slot in the bottom of the depression and which is provided with a pair of spring pawls *s* adapted to coöperate with the notched rear edge of the stationary bar *t*.

The gage plate *q* is provided on its face with three vertical columns numbered 1, 2 and 3. Number 1 column indicates single spaces; number 2 column, double spaces; and number 3 column, triple spaces. The gage will be so positioned on the supporting plate that when the lower edge of the plate *q* is adjusted to the 13 inch mark on said gage, the plate *q* will be in position to indicate at a glance to the operator the number of single, double and triple spaces on a 13-inch sheet after the sheet has been fed into the machine far enough to provide the desired top margin.

The gage plate *q* coöperates with gage B to perform one of the important objects of the invention, viz., approximately centering any desired number of lines on a page, or, in other words, to so position a certain number of lines on a page as to leave approximately an equal space at the top and bottom edges of the paper. This is accomplished in the following manner: Assuming that 13 inch paper is used, the gage *q* is set as in-

dicated in Fig. 2 with its bottom edge on the 13-inch line. The paper is then fed into the machine in the usual way, and, if it is desired to center 49 single-space lines or 25 double-space lines or 17 triple-space lines, the bottom edge of the paper is stopped when it reaches 49 in No. 1 column of the gage. This will space the first line to be written the proper distance from the top edge of the paper. When the bottom edge of the paper is first stopped at 49, it will be seen that this bottom edge will also register with space 29 on gage B; then, by adding 8 spaces (the distance lost around the platen) to the 29 and setting the alarm finger at 37 on gage B, the alarm will sound when the top edge of the paper reaches that point and the bottom line of the 49 desired lines will be spaced a distance from the bottom edge of the paper equal to the space left at the top of the sheet. It will thus be seen that the bottom edge of the paper acts in combination with both the gages B and *q*, one gage determining the width of the space at the top of the sheet and the other the width of the space left at the bottom of the sheet.

As before stated, six single-space lines to an inch is the usual typewriting spacing; therefore, on a sheet 13 inches long, there would be 78 lines, but 78 lines would extend from one extreme edge to the other, leaving no margin at the top and bottom of the sheet; so, to provide small blank spaces at the top and bottom, the gage *q* is preferably marked to allow 73 lines only, and, when centered on a 13-inch page, leave a blank margin at the top and bottom approximately one-half of an inch in width. In the same amount of printing space, 37 double-space and 25 triple-space lines can be written, and it will be observed from Fig. 4 of the drawings that the middle lines 13, 19 and 37 of the triple, double and single spaces, respectively, are placed in alinement; this will position lines 1 of the several columns in alinement and also the last lines 25, 37 and 73.

To provide a short length of gage, only alternate lines are designated by numbers, the even lines will, of course, be designated by the dividing lines.

Having thus described my invention, what I claim is:

1. A device of the class set forth, embodying a supporting plate having means for supporting it on a typewriting machine, and a gage means on said supporting plate having two separate columns of figures positioned to coöperate with the bottom edge of a sheet of paper of predetermined length started in the machine to indicate the placing of a predetermined number of lines of writing an equal distance from the top and bottom edges of the sheet.

2. The structure recited in claim 1, said gage means comprising a pair of gage plates.
3. The structure recited in claim 1, said gage means comprising a pair of gage plates one of which is adjustable on said supporting plate.
4. The structure recited in claim 1, said gage means comprising a pair of gage plates one of which is provided with an adjustable alarm adapted to be operated by the top edge of the sheet.

5. The structure recited in claim 1, said gage means comprising a pair of gage plates one of which is adjustable on said support-

ing plate and the other gage plate is provided with an adjustable alarm mechanism adapted to be operated by the top edge of the sheet.

6. The structure recited in claim 1, said gage means comprising a pair of gage plates one of which indicates the position of the first line of the matter to be written and the other indicating the position of the last line of the matter to be written.

GEORGE HENRY HERMANSEN.
